UNITED STATES PATENT OFFICE.

HOMER LE ROY BRISEIN, OF TOWNSEND, MONTANA.

WRENCH.

1,227,877.

Specification of Letters Patent. Patented May 29, 1917.

Application filed October 30, 1916. Serial No. 126,570.

To all whom it may concern:

Be it known that I, HOMER LE ROY BRIS-
BIN, a citizen of the United States, residing
at Townsend, in the county of Broadwater,
5 State of Montana, have invented certain new
and useful Improvements in Wrenches; and
I do hereby declare the following to be a
full, clear, and exact description of the in-
vention, such as will enable others skilled
10 in the art to which it appertains to make and
use the same.

This invention relates to improvements
in wrenches, and particularly to wrenches
for removing the cover of the transmission
15 gear of a Ford automobile.

One object of the invention is to provide
a simple and efficient device of this charac-
ter by means of which one man can quickly
and easily remove the bolts and nuts from
20 the gear casing or cover.

Another object is to provide a device of
this character by means of which the nut
is held stationary while the bolt is turned
therethrough for removing the same.

25 Another object is to provide a device of
this character wherein the nut and bolt will
be firmly held, and danger of either becoming
disengaged from the wrench reduced
to a minimum.

30 Other objects and advantages will be ap-
parent from the following description when
taken in connection with the accompanying
drawing.

In the drawing:

35 Figure 1 is a perspective view of a wrench
made in accordance with my invention.

Fig. 2 is a longitudinal sectional view
through the wrench and a portion of the
40 gear casing showing the action of the wrench
on the bolt and nut.

Referring particularly to the accompan-
ying drawing 10 represents, as a whole, a
frame, having two substantially U-shaped
members disposed in the same plane, as
45 shown at 11 and 12, respectively, the inter-
mediate arm 13 being common to both of
said members. Through the outer arm of
the member 11 is formed an opening 14,
and alining with this opening, and formed
50 in the intermediate arm, is an opening 15.
The outer end of the outer arm of the mem-
ber 12 is formed with a socket of a contour
to receive or embrace the nut 16, said open-

ing being represented at 17, and shown as
alining with the openings 14 and 15. Slid-
ably disposed through the alining openings
14 and 15 is a stem or shank 18, one end of
which is formed with an enlarged head 19,
disposed between the outer arm of the mem-
ber 12 and the intermediate arm 13, said 60
head having a socket 20 formed therein for
the reception of the head of the bolt 21. Dis-
posed through the stem or shank is a trans-
verse pin 22, and encircling the stem, be-
tween the pin and the arm of the member 11, 65
is a coil spring 23, said spring normally
urging the stem in a direction toward the
opening 17. The other end of the stem is
formed with an angular tapering enlarge-
ment 24 for reception in the socket of a 70
bit brace.

In the operation of the device, the U-
shaped member is placed in straddling re-
lation to the meeting edges of the gear cas-
ing, as clearly seen in Fig. 2, the opening 75
17 being engaged with the nut, while the
socket is disposed to receive the head of the
bolt. The spring will force the socket for-
ward so as to properly hold the bolt head,
and by turning the brace the stem will be 80
rotated in the alining openings, thereby ac-
complishing the turning of the bolt, while
the arm of the member 10 firmly holds the
nut. Thus the necessity of having a second
85 man to hold the bolt or nut while the other
is turned is completely obviated, one man
being able to remove both the bolt and nut,
alone. As the bolt recedes from the nut, the
spring is put under tension, automatically,
thereby increasing the holding power 90
thereof.

It will be noted that the device is of sim-
ple construction, and that it is formed of a
minimum number of parts, thereby con-
tributing to a reduction of the cost of man-
ufacture.

What is claimed is:

A wrench comprising a frame including a
pair of yoke members disposed in the same
plane and having a common connecting arm
100 formed with an opening in its extremity,
the arm of one of the said yoke members be-
ing formed with an opening alining with
the first opening, the arm of the other yoke
member being formed with a nut receiving 105
and holding opening, a stem slidably dis-

posed through the alining openings, a bit brace engaging member formed on one end of the stem, a bolt head socketed enlargement formed on the other end of the stem,
5 a transverse stop member carried by the stem between the common arm and the arm of the first named yoke member, and a coil spring encircling the stem between said

stop member and the said second-named arm.

In testimony whereof, I affix my signature, in the presence of two witnesses.

HOMER LE ROY BRISBIN.
